FABRIC WITH FLOAT DESIGN AREAS AND METHOD

Ivar O. Moberg, Spray, N. C., assignor to Fieldcrest Mills, Inc., Spray, N. C., a corporation of Delaware

Application November 13, 1953, Serial No. 392,732

23 Claims. (Cl. 139—419)

This invention relates to textile fabrics and, more especially, to a woven fabric having design areas formed therein by distorting and floating certain of the yarns thereof in a novel manner and wherein the fabric has the appearance and general characteristics of hand crocheted fabric, the principles of the invention being particularly applicable to the manufacture of bedspreads, drapes, curtains, stoles, hats and the like.

It is an object of this invention to provide a leno weave fabric having design areas therein in some of which substantial portions of the leno yarns are floated in X formations and having other areas therein in which the leno yarns are floated in Y formations and wherein the edges of at least some of the design areas formed from said floats extend at an angle relative to the warp and weft of the fabric.

It is another object of this invention to provide a leno weave fabric having a body portion in which warpwise extending lines or wales, formed from closely adjacent pairs of groups or tapes of leno face warp yarns, are interwoven with weft yarns in a serpentine manner and wherein tapes formed from the leno face warp yarns in each wale are spaced substantially from each other and floated over a substantial number of the weft yarns with the floated portions of the groups in each pair being drawn together in X or Y formations.

It is still another object of this invention to provide a leno weave fabric of the type last described wherein adjacent X formations formed from adjacent pairs of groups of said leno warp yarns are disposed in overlapping side by side relation and also wherein the marginal edges of areas having such X float formations therein extend at an angle relative to the warp and weft of the fabric.

It is another object of this invention to provide a method of weaving a fabric comprising loosely weaving a plurality of sets of approximately four ground warp yarns each in a leno weave with successive series of weft yarns, interlacing a plurality of sets of approximately four leno face warp yarns each at closely spaced points with each set of ground warp yarns to form relatively short floats therefrom on the under side of the fabric in forming a body portion, floating successive portions of each set of leno face warp yarns over a substantial number of the weft yarns and over the corresponding sets of ground warp yarns in angular relation to the warp and weft to form a row of leno face floats from each set of leno face warp yarns while varying the length of adjacent rows to produce variably-shaped ornamental float areas, and then shrinking the fabric to cause the weft yarns and ground warp yarns to draw together so the face floats have a loose sinuous appearance.

Some of the objects of the invention having been stated, other objects will appear as the description proceeds, when taken in connection with the accompanying drawings, in which—

Figure 1 is a somewhat schematic illustration of the improved leno weave fabric embodied in a bedspread

2

showing the ornamental design areas formed from the leno floats;

Figure 2 is a greatly enlarged view of the broken-line area indicated at 2 in Figure 1, showing the fabric as it is woven; that is, before being subjected to finishing operations, such as washing, bleaching and the like;

Figure 3 is a greatly enlarged fragmentary view of the broken-line area indicated at 3 in Figure 1, also showing the fabric as it is woven, that is, before it has been subjected to the usual finishing operations;

Figure 4 is a view similar to Figure 3, but showing the condition of the fabric after it has been washed.

Referring more specifically to the drawings, the letter A broadly designates a typical article of manufacture made from a fabric embodying the improved leno weave. Said article A is shown in Figure 1 in the form of a bedspread, but it is to be distinctly understood that the improved leno weave fabric may be used for the manufacture of many different types of articles, such as drapes, curtains, table coverings, stoles, hats, doilies and the like.

The article A includes a base, body or ground area B which has a plurality of ornamental design float areas or leno float areas superimposed thereon. The ornamental design areas may be of any desired shape or configuration, the ornamental design areas in the central portion of the article A each being indicated at 100 and being substantially diamond-shaped. Inner marginal areas 101 are also formed from leno floats along opposite side edges and the bottom of the body of the fabric shown in Figure 1, the inner edges of the marginal areas 101 being irregular according to the desired pattern.

Outside marginal areas or border areas 102 are superimposed over the ground fabric along the opposite side edges and bottom of the article A in Figure 1. In this instance, each of the areas 100 and 101 includes warpwise and weftwise extending rows of staggered leno floats shaped substantially in the form of the letter X and each of the border areas 102 includes a plurality of closely spaced rows of warpwise and weftwise extending rows of leno floats formed substantially in the form of the letter Y or V.

However, it is to be understood that the areas 100 and/or 101 may be provided with substantially Y-shaped or V-shaped leno floats and the areas 102 may be provided with substantially X-shaped floats, if desired, without departing from the spirit of the invention, the invention mainly residing in the provision of ornamental areas or zones formed from either X-shaped, Y-shaped or V-shaped leno floats wherein the edges of such areas extend at an angle relative to the warp and weft of the woven fabric.

In Figure 2, there is illustrated a portion of the fabric wherein the ornamental area defined by the leno float formations extends at an angle relative to the warp and weft of the woven fabric. In this instance, the leno floats are substantially in the shape of the letter X. The fabric in Figure 2 includes a ground fabric or a backing woven from a series of adjacent leno ground tapes or sets of leno ground warp yarns, each of which sets includes two complementary groups of leno ground warp yarns 10 and 11. In this instance, each of the groups 10 and 11 includes four parallel leno ground warp yarns. Each of said series of leno ground tapes 10 and 11 defines a wale, the wales shown in Figure 2 being indicated at a to e, inclusive.

The leno ground warp yarns 10 and 11 are loosely interwoven with ground weft yarns which, for purposes of description, are divided into successive groups indicated at 12 to 21, inclusive, in Figure 2. Each of the wales a through e also has a pair of leno face or effect tapes 22 and 23 which are complementary to the respective pairs of leno ground tapes 10 and 11.

Each of said leno face tapes or leno effect tapes includes a plurality of parallel leno face warp yarns or doup yarns. In this instance, each of the leno face tapes is formed from four leno face warp yarns. The groups of warp yarns 10, 11, 22 and 23 are termed as tapes only for purposes of distinction, since it is obvious that each tape comprises a plurality of relatively slack parallel leno warp yarns. The face yarns 22 and 23 are preferably, but not necessarily, of a softer and more pubescent texture than the groups of ground yarns 10 through 21.

In the body B of the fabric, the leno face tapes 22 and 23 cross back and forth above the corresponding groups of leno ground tapes 10 and 11 as shown in the weft yarn groups 12, 13 and 14 and the upper portions of wales a, b, d and e. It should be noted that, at the juncture of the weft yarn groups 12 and 13 in wales a, b, d and e, for example, the leno face tapes 22 and 23 are crossed over the corresponding leno ground tapes 10 and 11 and extend beneath the ground weft yarn groups 12 and 13, but alternately on opposite sides of the corresponding leno ground tapes 10 and 11. Thus, the leno face tapes 22 and 23 each extend in a serpentine or irregular path throughout that part of the lengths thereof which are disposed in the area or areas B other than the ornamental design areas.

Now, the ornamental float design areas 100 each includes a plurality of rows of floats, said rows being of varying lengths, and wherein the leno face tapes 22 and 23 in each wale a, b, c, d and e are floated over a substantial number of the ground weft yarns and are also floated over the corresponding leno ground tapes 10 and 11.

Each of the floats in each row or wale in Figure 2 is designated at F and it will be noted that at the beginning and end of each of said rows, the leno face tapes extend in substantially parallel relationship astraddle the corresponding portions of the leno ground tapes 10 and 11 and are floated beneath the ground weft yarns, such as the weft yarn group 12 in wale c.

The leno face tapes 22 and 23 then pass over, inwardly and across the corresponding leno ground tapes 10 and 11, that is, the two leno face tapes 22 and 23 converge inwardly after passing downwardly beneath a group of three tie-in ground weft yarns 13a of group 13 and then pass beneath an intermediate group of three tie-in ground weft yarns 13b, which are also a part of the group 13. However, the corresponding leno ground tapes 10 and 11 extend above the intermediate tie-in ground weft yarns 13b astraddle the face tapes 22 and 23 and then the leno face tapes 22 and 23 diverge and again cross over the corresponding leno ground tapes 10 and 11.

Thereafter, the leno ground tapes 10 and 11 pass above, and between the proximal edges of, the leno face tapes as the face tapes pass beneath a second outer group of tie-in ground weft yarns 13c, which are also a part of the group of weft yarns 13. Thus, the leno face tapes 22 and 23 in wale c are spaced substantially from each other since they pass beneath the outer group of tie-in ground weft yarns 13c and outwardly of the leno ground tapes 10 and 11.

The floated portions F of each of the tapes 22 and 23 are then floated downwardly from the tie-in group of ground warp yarns 13c and are superimposed across and above a plurality of the ground weft yarns including the yarns in group 14 and a few of those in group 15, the latter few being indicated at 15a. The group of ground weft yarns 15 not only includes the outer group of three tie-in weft yarns 15a, but also includes intermediate group of three tie-in or gathering ground warp yarns 15b and a second group of outer tie-in ground weft yarns 15c, the three groups 15a, 15b and 15c of the group of weft yarns 15 at wales b and d serving in the same capac-

ity as the groups 13a, 13b and 13c of the group 13 in the wale c.

However, referring again to the wale c, it will be observed that the intermediate group of tie-in ground weft 5 yarns 15b passes beneath the two groups of leno ground warp yarns 10 and 11 in wale c, but pass above the floats F of the leno face tapes 22 and 23 in wale c thereby drawing or gathering said floats together at this point. Thus, the floats F in wale c converge from the group of tie-in ground weft yarns 15c to the intermediate group of tie-in ground weft yarns 15b. Thereafter, reading downwardly from the intermediate group of tie-in weft yarns 15b, the floats F then diverge and pass beneath a group of three outer tie-in weft yarns 17a and outwardly of the corresponding leno ground tapes 10 and 11 in wale b which, contrary to the floats F of the leno face tapes 22 and 23 in wale c, pass above the outer tie-in weft yarns 17a.

The groups of weft yarns 17, 19 and 21 are also each 20 divided into three groups of three tie-in weft yarns in the same manner as the groups of ground weft yarns 13 and 15. Thus, the group of weft yarns 17 is divided into three groups of three tie-in weft yarns including outer tie-in weft yarns 17a and 17c and intermediate 25 tie-in weft yarns 17b. Of course, the group of ground weft yarns 19 includes outer groups of three tie-in weft yarns 19a and 19c and an intermediate group of three tie-in weft yarns 19b and the group of weft yarns 21 includes an outer group of three tie-in weft yarns 21a and 30 35 an intermediate group of three tie-in weft yarns 21b. It should be noted in wale c that the yarns in each of the leno ground tapes 10 and 11 are loosely interwoven with the weft yarns in each of the groups 12, 14, 15a, 15c, 16, 18, 19a, 19c and 20, but all of the yarns in each tape 10 and 11 pass above all the weft yarns in each of the groups 13a, 13b, 13c, 15b, 17a, 17b, 17c, 19b, 21a and 21b. On the other hand, all the yarns in each leno face tape pass beneath all the weft yarns except where the face floats F are present.

40 It is thus seen that a plurality of rows of X-shaped floats F are formed in the wales a, b, c, d and e in which the junctures of adjacent X-shaped floats F in each wale are tied into the ground fabric formed from the ground warp yarns or leno ground tapes 22 and 23 and the ground weft yarns by means of three groups of three tie-in weft yarns in the manner heretofore described with respect to the outer and intermediate ground weft yarns 13a, 13b and 13c in wale c.

45 It should be noted that the length of each of the rows 50 of X-shaped floats F may vary as desired and, in particular, it will be noted that the spaced upper and lower ends of each of the floats in the wales b and d are tied into the fabric substantially midway of the adjacent X-shaped floats F in the wale c therebetween. Thus, the X-shaped floats F are disposed in staggered relationship in adjacent 55 wales. Since all of the floats F in each row are constructed and tied into the base or ground fabric formed from the ground warp yarns and the ground weft yarns in the same manner, a further detailed description of Figure 60 2 is deemed unnecessary.

The fabric structure shown in Figures 3 and 4 includes wales g, h and i, each of which wales includes two groups of parallel leno ground warp yarns or leno ground tapes 10a and 11a and two groups of leno face warp yarns or 65 leno face tapes 22a and 23a. The portion of fabric shown in Figure 3 also includes successive groups of ground weft yarns 25 to 33, inclusive, reading from top to bottom. The structure shown in Figure 3 is quite similar to that shown in Figure 2 with the exception of the configuration of the floats thereof, which floats are indicated at F-1. It should be noted that the floats F-1 in Figures 3 and 4 are disposed in staggered relationship in adjacent wales and the floats F-1 are substantially Y-shaped or V-shaped.

70 In other words, the portions of the floats F-1 disposed

above intermediate groups of tie-in ground weft yarns, such as group 27a in wale *h* and group 31a in wales *g* and *i*, extend upwardly in parallel relationship to the point at which they are tied into the base fabric, these upper parallel portions of the floats F-1 being floated above the corresponding ground weft yarns and between the leno ground tapes 10a and 11a, the yarns in each of said leno ground tapes being loosely interwoven with the corresponding ground weft yarns.

The portions of the leno face tapes 22a and 23a forming the lower portion of each of the floats F-1 in Figures 3 and 4 diverge from the corresponding tie-in weft yarns and, in so doing, extend above the corresponding leno ground tapes 10a and 11a as well as a substantial number of the ground weft yarns. The lower ends of the floats formed from each pair of leno face tapes 22a and 23a are held in spaced relationship in identically the manner heretofore described with respect to the structure shown in Figure 2. For example, it will be noted that an outer group of tie-in weft yarns 33a, which are a part of the group 33, pass beneath the leno ground tapes 10a and 11a in wale *g*. On the other hand, the leno face tapes 22a and 23a extend beneath the outer tie-in group of weft yarns 33a and are disposed astraddle the complementary leno ground tapes 10a and 11a.

The backing or ground fabric formed in those portions of the wales between adjacent floats F-1 in Figures 3 and 4 is woven in substantially the same manner as that described with respect to the structure shown in Figure 2, in which relatively short spaced floats are formed underneath the fabric or beneath corresponding weft yarns from the leno face tapes 22a and 23a in each wale, these relatively short floats being alternately formed between and astraddle the complementary leno ground tapes 10a and 11a, with the leno ground tapes being interwoven with the corresponding ground weft yarns in substantially the manner described with respect to Figure 2. It is therefore believed that a further detailed description of the structure shown in Figures 3 and 4 is unnecessary.

As heretofore stated, in Figure 3, the portion of fabric shown is illustrated as it is woven or as it comes off the loom and the portion of fabric shown in Figure 4 shows the appearance of the fabric portion of Figure 3 after it has been washed. Since the leno face yarns 22a and 23a are floated for substantially the entire length thereof and may also be woven under slightly lesser tension than that of the leno ground tapes 10a and 11a, the leno ground tapes 10a and 11a and the ground weft yarns tend to shrink a substantially greater amount than that of the leno face tapes or leno face warp yarns 22a and 23a when the fabric is washed. This produces a fluffy texture in the floats F-1, as illustrated in Figure 4, so the floats F-1 are loosely superimposed upon the ground fabric.

Although Figure 4 is an illustration of the fabric shown in Figure 3 after it has been washed, it is apparent that the floats F in the portion of the fabric shown in Figure 2 would also have a similar appearance to that of the floats F-1 in Figure 4 when the fabric of Figure 2 is washed.

It is thus seen that I have provided an improved fabric structure and method of producing same which comprises a leno-base fabric or backing, in portions of which ornamental design areas are formed, such ornamental design areas including rows of leno floats in which the floats extend at an angle relative to the weft and warp of the fabric and wherein the floats in adjacent rows are disposed in staggered relationship from row to row and also wherein the rows are of varying length so that the general configuration of each ornamental design area is varied, that is, so the edges of areas defined by said adjacent rows of floats, or portions of said edges, extend at an angle relative to the warp and weft of the fabric. After the fabric is woven it is washed to shrink the same so as to draw the base fabric, which is formed by open-weaving, to shrink and become closed. This causes the floats in each row to have a loose sinuous appearance.

Throughout the specification and some of the claims, the term "leno" where used is to be construed in its broadest sense and refers, in particular, to a face warp yarn or group of face warp yarns having portions which 5 pass back and forth across a complementary base yarn or complementary groups of base warp yarns and which are locked in such positions by weft yarns, such as the portions of the tapes 10 and 11 in wale *c*, between the groups of weft yarns 13a and 13c, in the upper portion of Figure 2. With this exception, fabrics constructed in accordance with the present invention are completely different from conventional leno weave fabrics as they are currently known in the art, since the effect produced by the face warp tapes is, to my knowledge, a new construction heretofore unknown in the art. Also, it is contemplated that the plain weave between and underlying the face floats may be substituted by more attractive and intricate weaves than that shown in Figures 2, 3 and 4, all within the concept of the present invention.

In the drawings and specification there has been set forth a preferred embodiment of the invention and, although specific terms are employed, they are used in a generic and descriptive sense only, and not for purposes of limitation, the scope of the invention being defined 20 in the claims.

I claim:

1. A fabric having a body portion formed from interwoven ground warp yarns and ground weft yarns, ornamental areas formed in portions of said body portion each 30 including a plurality of rows of floats, each row including a plurality of aligned floats, said rows being of varying length, and each of said floats, at least in part, extending at an angle relative to, and above, a plurality of said ground weft yarns.

2. A fabric having a base formed from interwoven ground warp yarns and ground weft yarns, at least one ornamental area formed in said base comprising a plurality of rows made from spaced groups of facing yarns and each row including a plurality of recurrent floats 40 formed from said facing yarns, and said floats, in part at least, extending at an angle to, and above, a plurality of said ground weft yarns and a plurality of said ground warp yarns.

3. A fabric having a base formed from interwoven 45 ground warp yarns and ground weft yarns, at least one ornamental area formed in said base comprising a plurality of rows made from spaced groups of facing yarns and each row including a plurality of recurrent floats formed from said facing yarns, and adjacent floats being drawn together intermediate their ends and bound to the 50 base by certain of said ground weft yarns to produce a substantially X-shaped formation to said floats.

4. A fabric having a base formed from interwoven ground warp yarns and ground weft yarns, at least one 55 ornamental area formed in said base comprising a plurality of rows made from spaced groups of facing yarns and each row including a plurality of recurrent floats formed from said facing yarns, adjacent floats being drawn together intermediate their ends and bound to the base by certain of said ground weft yarns to produce a substantially X-shaped formation to said floats, and adjacent X-shaped floats in adjacent rows being disposed in staggered relationship.

5. A fabric having a base formed from interwoven 60 ground warp yarns and ground weft yarns, at least one ornamental area formed in said base comprising a plurality of rows made from spaced groups of facing yarns and each row including a plurality of recurrent floats formed from said facing yarns, corresponding end portions of adjacent floats in each adjacent pair of rows being disposed in juxtaposed relationship and extending across, and above, a substantial number of said weft yarns, the other end portions of said last-named adjacent floats 70 extending in divergent relationship from the juxtaposed portions thereof, and a few of said weft yarns passing

over the floats at the juncture of the juxtaposed and divergent portions thereof to tie the medial portions of said adjacent floats into the base whereby said adjacent floats collectively have a substantially Y-shaped form.

6. A fabric having a base formed from interwoven ground warp yarns and ground weft yarns, at least one ornamental area formed in said base comprising a plurality of rows made from spaced groups of facing yarns and each row including a plurality of recurrent floats formed from said facing yarns, corresponding end portions of adjacent floats in each adjacent pair of rows being disposed in juxtaposed relationship and extending across, and above, a substantial number of said weft yarns, the other end portions of said last-named adjacent floats extending in divergent relationship from the juxtaposed portions thereof, a few of said weft yarns passing over the floats at the juncture of the juxtaposed and divergent portions thereof to tie the medial portions of said adjacent floats into the base whereby said adjacent floats collectively have a substantially Y-shaped form, the Y-shaped floats in each pair of rows being spaced apart, and the adjacent Y-shaped floats being in staggered relationship weftwise of the fabric.

7. A woven fabric having a body formed from interwoven weft yarns and ground warp yarns, wales formed in said body from successive weftwise spaced warpwise extending leno tapes generally extending beneath the warp yarns and the weft yarns and being interlaced with the latter at substantially uniformly spaced points warpwise of the fabric, ornamental design areas formed in said fabric, each area comprising a plurality of rows each including one or more floats therein, each of said rows embracing a wale, each of said floats including a portion of the corresponding leno tape floated over the corresponding ground warp yarns in angular relationship thereto and being floated over a substantial number of said weft yarns.

8. A woven fabric having a body formed from interwoven weft yarns and ground warp yarns, wales formed in said body from successive weftwise spaced warpwise extending leno tapes generally extending beneath the warp yarns and the weft yarns and being interlaced with the latter at substantially uniformly spaced points warpwise of the fabric, each of said leno tapes including a plurality of face warp yarns, ornamental design areas formed in said fabric, each area comprising a plurality of variable-length rows each including one or more floats therein, each of said rows embracing a wale, each of said floats including a portion of the corresponding leno tape floated over the corresponding ground warp yarns in angular relationship thereto and being floated over a substantial number of said weft yarns.

9. A woven fabric having a body formed from interwoven weft yarns and ground yarns, wales formed in said body from successive warpwise extending pairs of leno tapes generally extending beneath the warp yarns and the weft yarns and being interlaced with the latter at substantially uniformly spaced points warpwise of the fabric, the leno tape in each wale being spaced from each other, ornamental design areas formed in said fabric, each area comprising a plurality of rows each including one or more floats therein, each of said rows embracing a wale, each of said floats including adjacent portions of complementary pairs of leno tapes floated over the corresponding ground warp yarns in angular relationship thereto and being floated over a substantial number of said weft yarns, and edges of said areas, at least in part, extending at an angle relative to the weft yarns.

10. A woven fabric having a body formed from interwoven weft yarns and ground warp yarns, wales formed in said body from successive warpwise extending pairs of leno tapes generally extending beneath the warp yarns and the weft yarns and being interlaced with the latter at substantially uniformly spaced points warpwise of the fabric, the leno tapes in each wale being spaced from each

other, ornamental design areas formed in said fabric, each area comprising a plurality of rows each including one or more floats therein, each of said rows embracing a wale, each of said floats including adjacent portions of complementary pairs of leno tapes floated over the corresponding ground warp yarns in angular relationship thereto and being floated over a substantial number of said weft yarns, edges of said areas, at least in part, extending at an angle relative to the weft yarns, and at least a portion of said adjacent portions in each wale being drawn together beneath at least one of said weft yarns to produce a substantially V-shaped formation to each float.

11. A woven fabric having a body formed from interwoven weft yarns and ground warp yarns, wales formed in said body from successive warpwise extending pairs of leno tapes generally extending beneath the warp yarns and the weft yarns and being interlaced with the latter at substantially uniformly spaced points warpwise of the fabric, the leno tapes in each wale being spaced from each other, ornamental design areas formed in said fabric, each area comprising a plurality of rows each including one or more floats therein, each of said rows embracing a wale, each of said floats including adjacent portions of complementary pairs of leno tapes floated over the corresponding ground warp yarns in angular relationship thereto and being floated over a substantial number of said weft yarns, edges of said areas, at least in part, extending at an angle relative to the weft yarns, and portions of the pair of tapes forming each float being bound together intermediate the ends of each float to produce a substantially X-shaped formation to each float.

12. A woven fabric having a body formed from interwoven weft yarns and ground warp yarns, wales formed in said body from successive warpwise extending pairs of leno tapes generally extending beneath the warp yarns and the weft yarns and being interlaced with the latter at substantially uniformly spaced points warpwise of the fabric, the leno tapes in each wale being spaced from each other, ornamental design areas formed in said fabric, each area comprising a plurality of rows each including one or more floats therein, each of said rows embracing a wale, each of said floats including adjacent portions of complementary pairs of leno tapes floated over the corresponding ground warp yarns in angular relationship thereto and being floated over a substantial number of said weft yarns, edges of said areas, at least in part, extending at an angle relative to the weft yarns, corresponding end portions of the two leno tape portions forming each float extending in parallel juxtaposition between the adjacent ground warp yarns and over a substantial number of said weft yarns, binder weft yarns tying the medial portions of the portions of said two leno tapes forming said floats together, and the other end portions of the two tapes forming each float extending in divergent relationship from the corresponding binder weft yarns to produce a substantially Y-shaped formation to each float.

13. A woven fabric having a body formed from ground warp yarns interwoven with ground weft yarns, said ground warp yarns being divided into groups to form ground tapes and each pair of ground tapes defining a wale, each wale also including a plurality of leno face warp yarns divided into two groups to form face tapes floated beneath the weft yarns and being interlaced with the respective ground tapes at spaced points so they successively pass between and astraddle the ground tapes in the corresponding wale, at least one design area formed on said body comprising a plurality of contiguous rows each having a plurality of face floats therein, said rows being of varying length, each of said face floats being formed from the face tapes of the corresponding wale wherein a substantial portion of each face tape is floated over a substantial number of said weft yarns and over the respective ground tapes, and the medial portions of the two face tapes forming each face float being drawn

together and tied into the body so the face floats are substantially X-shaped.

14. A woven fabric having a body formed from ground warp yarns interwoven with ground weft yarns, said ground warp yarns being divided into groups to form ground tapes and each pair of ground tapes defining a wale, each wale also including a plurality of leno face warp yarns divided into two groups to form face tapes floated beneath the weft yarns and being interlaced with the respective ground tapes at spaced points so they successively pass between and astraddle the ground tapes in the corresponding wale, at least one design area formed on said body comprising a plurality of contiguous rows each having a plurality of face floats therein, said rows being of varying length, each of said face floats being formed from the face tapes of the corresponding wale wherein a substantial portion of each face tape is floated over a substantial number of said weft yarns and over the respective ground tapes, and corresponding portions of the two face tapes forming each face float being drawn together and tied into the body so they extend in angular relationship to the weft yarns and the ground tapes.

15. A woven fabric having a body formed from ground warp yarns interwoven with ground weft yarns, said ground warp yarns being divided into groups to form ground tapes and each pair of ground tapes defining a wale, each wale also including a plurality of leno face warp yarns divided into two groups to form face tapes floated beneath the weft yarns and being interlaced with the respective ground tapes at spaced points so they successively pass between and astraddle the ground tapes in the corresponding wale, at least one design area formed on said body comprising a plurality of contiguous rows each having a plurality of face floats therein, said rows being of varying length, each of said face floats being formed from the face tapes of the corresponding wale wherein a substantial portion of each face tape is floated over a substantial number of said weft yarns and over the respective ground tapes, binder weft yarns tying the medial portions of the portions of the two face tapes forming each face float together, corresponding ends of said portions of the two face tapes forming each float diverging from said binder weft yarns, and their other ends extending in parallel juxtaposition from said binder weft yarns.

16. A woven fabric having a body formed from a plurality of ground weft yarns, a plurality of contiguous warpwise wales each including a pair of leno ground tapes and a pair of leno face tapes respectively formed from a plurality of ground warp yarns and a plurality of face warp yarns, said ground warp yarns being interwoven with said weft yarns to form a base fabric, first portions of said face tapes in each wale being floated beneath said weft yarns astraddle the corresponding pair of ground tapes at spaced points and second portions thereof between adjacent first portions being floated beneath said weft yarns, but between the corresponding pair of ground tapes, said face tapes in each wale being crossed over the corresponding ground tapes at the junctures of said first and second portions to tie the face tapes to the base fabric, at least one ornamental design area formed in said body and comprising a plurality of variable-length contiguous rows of face floats, each of said rows comprising a plurality of the face floats arranged in series and being formed from said face tapes wherein the face tapes in each wale are disposed astraddle the corresponding pair of ground tapes and interlaced with certain of the weft yarns at opposite ends of each face float, said face tapes being floated over a substantial number of said weft yarns and over the ground tapes at said face floats, and the medial portions of the face tapes in each wale at each face float being drawn together by a few of said weft yarns so each face float is substantially X-shaped.

17. A woven fabric having a body formed from a plurality of ground weft yarns, a plurality of contiguous

warpwise wales each including a pair of leno ground tapes and a pair of leno face tapes respectively formed from a plurality of ground warp yarns and a plurality of face warp yarns, said ground warp yarns being interwoven with said weft yarns to form a base fabric, first portions of said face tapes in each wale being floated beneath said weft yarns astraddle the corresponding pair of ground tapes at spaced points and second portions thereof between adjacent first portions being floated beneath said weft yarns, but between the corresponding pair of ground tapes, said face steps in each wale being crossed over the corresponding ground tapes at the junctures of said first and second portions to tie the face tapes to the base fabric, at least one ornamental design area formed in said body and comprising a plurality of variable-length contiguous rows of recurrent face floats, each of said face floats being formed from said face tapes wherein the face tapes in each wale are disposed astraddle the corresponding pair of ground tapes and interlaced with certain of the weft yarns at one end of each face float, the face tapes being interlaced with certain others of the weft yarns and between the corresponding ground tapes at the other end of each face float, said face tapes being floated over a substantial number of said weft yarns and over the ground tapes at said face floats, and the medial portions of the face tapes in each wale at each face float being drawn together by a few of said weft yarns so each face float is substantially Y-shaped.

18. A woven fabric having design areas therein, at least some of which include a plurality of parallel rows of floats, certain of said rows of floats being longer than others of said rows of floats, said floats in each row being formed from a pair of leno tapes each including a plurality of parallel yarns, portions of said tapes in each row being disposed in juxtaposition, and the portions of said tapes in each row forming said floats extending in diverging relationship from the points at which said tapes are disposed in juxtaposition.

19. As an article of manufacture, a fabric woven from ground weft yarns and ground warp yarns, a plurality of generally parallel leno face tapes each including a plurality of juxtaposed leno warp yarns interwoven with said ground warp and ground weft yarns, said leno face tapes being bent out of their otherwise straight course of extent at predetermined spaced points, design areas formed in said fabric by said tapes being floated over a substantial portion of said ground warp yarns and said ground weft yarns, there being a plurality of contiguous warpwise extending rows of said floated portions of said tapes, adjacent complementary pairs of said tapes being drawn together intermediate the ends of each of said floated portions thereof, the opposite ends of each of said adjacent pairs of floated portions being tied into the ground fabric formed from the ground weft yarns and the ground warp yarns in substantially spaced relation to each other whereby the floated portions of said complementary pairs of tapes extend at an angle relative to said ground weft yarns and said ground warp yarns, and at least some of said rows of floated portions of said tapes terminating at opposite ends thereof at certain weft yarns spaced from other weft yarns at which others of said rows of floated portions of said tapes terminate.

20. A woven fabric formed from a plurality of warp yarns, a plurality of weft yarns interwoven with said warp yarns, leno face warp yarns interwoven with said ground warp yarns and said ground weft yarns in alternation throughout their lengths and being diverted from their regular path so they extend in a serpentine path, design areas formed from said leno warp yarns, at least one of said design areas including a plurality of adjacent warpwise extending rows of floats, said rows being of varying lengths, each of said rows of floats being formed from portions of a pair of closely adjacent groups of said leno face warp yarns wherein said pair are interwoven with the ground weft yarns in juxtaposition at spaced points

and are interwoven with the ground warp yarns in substantially spaced relationship at other points spaced from said spaced points to cause the floats to extend at an angle relative to the ground weft yarns and the ground warp yarns.

21. A method of making a portion of fabric which comprises weaving a plurality of adjacent complementary groups of at least two face warp yarns and at least two ground warp yarns in a leno weave with spaced groups of at least two weft yarns to form leno loops thereat, interweaving the ground warp yarns with second groups of a greater number of weft yarns than that of said spaced groups in a plain open weave between adjacent pairs of said spaced groups while floating portions of the groups of face warp yarns beneath some successive second groups of weft yarns, forming rows of face floats by successively floating other portions of said groups of face warp yarns over, and in angular relation to, the corresponding groups of ground warp yarns as well as other successive second groups of weft yarns, varying the number of face floats in adjacent rows, and then shrinking said fabric portion to cause the weft yarns and ground warp yarns to draw together so the face floats have a sinuous appearance.

22. A method of making a portion of fabric which comprises weaving a plurality of substantially parallel complementary groups of at least two face warp yarns and at least two ground warp yarns in a leno weave with first spaced groups of at least two weft yarns each to form leno loops thereat, interweaving, in a plain open weave, the ground warp yarns with a plurality of second groups of a greater number of weft yarns than that of said first groups so there is one of said second groups between each adjacent pair of said first groups and while floating successive first portions of the groups of face warp yarns beneath certain successive second groups of weft yarns,

forming rows of face floats by successively floating other portions of said groups of said face warp yarns over the corresponding groups of ground warp yarns and successive sets of two second groups of weft yarns so each successive face float embraces two of said second groups of weft yarns, drawing the medial portions of each adjacent pair of face floats together to produce an X shape to said last-named face floats, varying the number of X-shaped face floats so formed from row to row, and then shrinking said fabric portion to cause the weft yarns and ground warp yarns to draw together so the face floats have a sinuous appearance.

23. In a method of making a fabric from face warp yarns, ground warp yarns and weft yarns; the steps of forming adjacent parallel rows of substantially X-shaped floats from adjacent groups of said face warp yarns while weaving said weft yarns in a plain open weave with said ground warp yarns beneath said rows of floats, varying the length of at least two of said rows, and then shrinking said fabric to cause the ground warp yarns and weft yarns to draw together so the floats have a loose and sinuous appearance.
